UNITED STATES PATENT OFFICE.

FRANCIS WITZMANN, OF NEW YORK, N. Y., ASSIGNOR OF ONE-HALF TO
ALEXANDER MONAGHAN, OF NEW ORLEANS, LOUISIANA.

SCRAPER.

SPECIFICATION forming part of Letters Patent No. 643,314, dated February 13, 1900.

Application filed October 12, 1899. Serial No. 733,375. (No model.)

To all whom it may concern:

Be it known that I, FRANCIS WITZMANN, a citizen of the United States, residing in New York city, borough of Manhattan, State of New York, have invented certain new and useful Improvements in Scrapers or Planers, of which the following is a specification.

The object of my invention is to produce a simple and efficient device capable of use in scraping brands, labels, and the like from boxes, barrels, &c., and also serviceable for scraping or planing other wooden surfaces; and the invention consists in the novel details of improvement that will be more fully 15 hereinafter set forth and then pointed out in the claims.

Reference is to be had to the accompanying drawings, forming part hereof, wherein—

Figure 1 is a side elevation of my improvement, partly in section, on the plane of the line $x'x'$ in Fig. 2. Fig. 2 is a face view thereof, the handle being in section on the line xx in Fig. 1. Fig. 3 is a detail sectional view on the line yy in Fig. 1 looking in the direction 25 of the arrow. Fig. 4 is a cross-section on the plane of the line zz in Fig. 5; and Fig. 5 is a face view thereof, Figs. 4 and 5 showing a form of adjustable handle.

In the accompanying drawings, in which 30 similar numerals of reference indicate corresponding parts in the several views, 1 indicates generally a frame which is shown provided with a bottom wall 2, having an opening 3 extending transversely of the frame, an upwardly and rearwardly inclined wall or 35 ledge 4 extending from opening 3, and upwardly and rearwardly extending opposed sides 5, an open space being thereby formed between the bottom wall 2 and the sides 5.

Upon the wall or ledge 4 a cutting-blade 6 is 40 adapted to rest, so that its lower cutting edge may project more or less through the opening 3 into the cutting position. The sides 5 are preferably provided with opposed grooves 7, 45 in which the side edges of the blade 6 are adapted to pass, which grooves are contiguous to the wall or ledge 4, so that the blade may rest upon the latter. (See Figs. 1 and 4.) Upon the blade 6 rests a clamp 8, which extends 50 across the frame and whose side edges lie in the grooves 7, and the upper end of the

clamp 8 extends beyond the back edges of the sides 5 of frame 1. At the upper corners of said clamp are located projections or lugs 8^a, which bear against the back edges 5^a of sides 5, whereby the distance that the clamp 8 can pass into the frame 1 is regulated. In other words, when the clamp 8 is placed in the frame it is pushed downwardly along the grooves 7 until its projections 8^a abut against the sides 5, whereupon the lower edge of the clamp lies near opening 3, and the position of the clamp 8 is thus regulated in the frame. It will be seen that the edge 8^b of clamp 8 is inclined upwardly from the blade 6 above the opening 3 to allow clearance for shavings or chips. The clamp 8 is to be pressed firmly upon the blade 6 to hold the latter in the operative position, and for this purpose I have provided screws 9, which mesh in threaded bores 70 10 in the sides 5 of the frame, which bores open above the clamp 8, so that the screws 9 can bear upon the latter. In line with the bores 10 the clamp 8 is provided with counterbores or recesses 11 to receive the ends of 75 screws 8 to prevent the clamp from being shifted by the rotation of the screws while in contact therewith.

In order to enable the scraper or planer to be conveniently and strongly manipulated, I 80 provide one or more handles 12 13, which are shown arranged centrally of frame 1 and connected to a cross-bar 14, that is attached to the sides 5 of the frame. The cross-bar 14 may be cast integral with the sides 5, as indicated in Figs. 1 and 2, and the handles 12 13 may be removable therefrom, for which purpose the cross-bar 14 is shown provided with projections or lugs 15 16, the handle 12 being shown connected with the projection 15 85 and the handle 13 connected with projection 16. For this purpose handle 12 is provided with a screw-threaded end 12^a, meshing in a threaded bore 15^a in projection 15, and handle 13 is provided with a screw-threaded end 90 13^a, meshing in a threaded bore 16^a in projection 16. By this means the handles can be readily removed for convenience in storing and shipping the device. It will be seen that handle 12 projects from the planer at an acute angle to the plane of the rubbing-face 95 of wall 2, which I find to be an advantageous

position for the handle, so as to afford great strength in manipulating the device. The handle 13 is shown extending in line with the vertical axis of frame 1, and the position of these handles is such that a strong downward pressure can be exerted at the same time with a strong pulling action for scraping or planing surfaces.

In Figs. 4 and 5 the support for the handles or the bar 14 is shown movably connected with the sides 5, for which purpose it is shown swiveled on a rod or bolt 17, that passes through apertures in the sides 5 and through a bore in the bar 14, and it is shown provided with a head 17^a at one end and a nut 17^b at the opposite end for holding it securely in the frame. The projections 15 and 16 extend from bar 14, as more clearly shown in Fig. 4, and in order to keep the bar 14 from rotating, so that the handles 12 and 13 will be held rigidly in the operative position, I have provided a cross-bar 18, that rests upon the tops of the sides 5 and which is provided with a central aperture 18^a to receive the threaded end of handle 13. The position of projection 16 is such that when the threaded part 13^a of handle 13 passes through aperture 18^a of cross-bar 18 and meshes with threads 16^a in projection 16 of bar 14 the handle 12 will be rigidly held in the operative position for pulling the scraper, as indicated by dotted lines in Fig. 4. In some instances it may be desirable to push the scraper or planer, and in this case the handle 13 and bar 18 may be removed and the handle 12 swung over behind the frame 1, as shown in full lines in Fig. 4, (the bar 14 rotating on its support 17,) and to firmly lock the handle 12 in this position the bar 14 is provided with a projection 20 on the side opposite the projection 16, the projection 20 being provided with a threaded bore 20^a to receive the threaded end 13^a of handle 13, the position of projection 20 being such that when handle 13 is secured to the same through the cross-bar 18 handle 12 will extend and be held in the proper operative position. The cross-bar 18 is preferably rigidly connected with the sides 5 of the frame 1, and for this purpose I have shown screws 21, that pass through apertures in cross-bar 18 and mesh in threaded bores 22 in the upper ends of sides 5. (See Fig. 5.) By this means the cross-bar 18 can be readily detached from the sides 5 to enable the handle 12 to be adjusted either to the front or back of the frame 1, and when replaced and held by the screws 21 will serve to lock the handle 12 in either working position.

I do not limit my invention to the details of construction shown and described, as they may be varied without departing from the spirit thereof.

Having now described my invention, what I claim is—

65

1. In a planer or scraper, the combination of a frame having a bottom wall provided with an opening, and sides projecting above the same, a blade, means for holding the blade in the frame, a handle-support located between said sides and having threaded portions situated at an angle to each other, and handles for connection with said support, substantially as described.

70

2. In a planer or scraper, the combination of a frame having a bottom wall provided with an opening and sides projecting above the same, a blade, means for holding the blade in the frame, a bar supported between said sides, said bar having a pair of projections extending at an angle to each other, and handles for connection with said projections, substantially as described.

75

3. In a planer or scraper, the combination of a frame having a pair of opposed sides, means for holding a blade in the frame, a handle-support movably connected with said sides, a bar extending across the frame in connection with said sides, and means for securing said handle-support to said bar, substantially as described.

80

4. In a planer or scraper, the combination of a frame having a pair of opposed sides, means for holding a blade in the frame, a handle-support movably carried by said frame, said support having means for attaching a handle thereto, a cross-bar to be connected with said sides, and means for securing the handle-support to said cross-bar, substantially as described.

85

5. In a planer or scraper, the combination of a frame having a pair of opposed sides, means for holding a blade in the frame, a handle-support, a bar secured to said sides upon which said handle-support is mounted to rotate, a cross-bar, means for connecting it with said sides, said handle-support having means for attaching a handle thereto, and means for attaching a handle to the support through the medium of said cross-bar, substantially as described.

90

6. In a planer or scraper, the combination of a frame having a pair of opposed sides, means for holding a blade in the frame, a handle-support, means for rotatively supporting the same in the frame, said handle-support having means for attaching a handle thereto and also having opposed threaded portions, a cross-bar, means for securing the same to the sides, and a handle having means for connecting it to the handle-support through said cross-bar, substantially as described.
